COMBINED PEW AND KNEELER

James Clark, Chappaqua, N. Y., assignor to The Gothic Altar Studio, Incorporated, Katonah, N. Y., a corporation of New York

Application December 9, 1954, Serial No. 33,465

Term of patent 14 years

(Cl. D15—1)

I claim:

The ornamental design for a combined pew and kneeler, substantially as shown.
